UNITED STATES PATENT OFFICE.

WILLIAM W. BROOKS, OF MEMPHIS, TENNESSEE, ASSIGNOR OF ONE-HALF
TO THOMAS W. CARTER, OF SAME PLACE.

PROPELLING MECHANISM FOR BICYCLES.

SPECIFICATION forming part of Letters Patent No. 611,557, dated September 27, 1898.

Application filed December 6, 1897. Serial No. 660,894. (No model.)

To all whom it may concern:

Be it known that I, WILLIAM W. BROOKS, a citizen of the United States, residing at Memphis, in the county of Shelby and State of Tennessee, have invented a new and useful Propelling Mechanism for Bicycles, of which the following is a specification.

The invention relates to improvements in propelling mechanism for bicycles of that class which employ treadle-levers adapted to reciprocate vertically as distinguished from rotary cranks for the operation of a sprocket-wheel connected by an intermediate chain with the rear hub of the bicycle.

One of the objects of my invention is to provide an improved propelling mechanism in which the upward or lifting movement of the treadle-levers is effected in a positive manner by connections with the sprocket-wheel or treadle-lever shaft, thus dispensing with a spring-and-ratchet drum for the elevation of the treadle-levers.

A further object of the invention is to so construct and arrange the various parts that the propelling mechanism may be utilized under certain conditions as a brake to arrest or retard the travel of the bicycle.

A further object of the invention is to provide a novel form of clutch mechanism to permit the treadle-lever to move in an upward direction very freely and with minimum resistance, but which operates to couple the treadle-lever rigidly and securely to its shaft on the downstroke of the lever under the pressure of the rider.

With these ends in view my invention consists in the novel combination of elements and in the construction and arrangement of parts, which will be hereinafter fully described and claimed.

To enable others to understand my invention, I have illustrated the same in the accompanying drawings, forming a part of this specification, and in which—

Figure 1 is a side elevation of part of a bicycle with my improved propelling-gear applied thereto. Fig. 2 is a vertical transverse sectional view through the treadle-shaft on the plane indicated by the dotted line 2 2 of Fig. 1. Fig. 3 is a similar transverse sectional view through the crank-shaft indicated by

the dotted line 3 3 of Fig. 1. Fig. 4 is an enlarged view, in side elevation, of one form of sprocket-wheel and clutch mechanism which may be used in connection with the treadle-shaft of the propelling mechanism. Fig. 5 is a vertical transverse section. Figs. 6, 7, and 8 are views in longitudinal section, transverse section, and perspective, with the members detached, of another embodiment of the clutch mechanism which may be used in my invention. Fig. 9 is a view in side elevation of another form of clutch mechanism for use in connection with one of the treadle-levers. Fig. 10 is a longitudinal section through the clutch and lever shown by Fig. 9. Fig. 11 is a detail perspective view showing the parts detached forming the clutch illustrated by Figs. 9 and 10. Fig. 12 is a detail view of the crank for use in connection with the clutch shown by Figs. 9, 10, and 11. Fig. 13 is a detail view, in side elevation, of one treadle-lever to be used in connection with the clutch shown by Figs. 1 to 5, inclusive. Figs. 14 and 15 are views of a modified form of the link connection between the crank-shaft and the treadle-lever.

Like numerals of reference denote corresponding parts in each of the several figures of the drawings.

The framework of the bicycle is of ordinary construction, except that I provide on the inclined reach between the steering-head and the crank-hanger a bearing 1 for a crank-shaft. As is usual, the crank-hanger is united to the seat-post socket, the rear fork, and the inclined front reach, and in this crank-shaft hanger 2 is journaled a transverse treadle-shaft 3. The ends of this treadle-shaft protrude for suitable distances beyond the ends of the crank-hanger, and on said protruding ends of the treadle-shaft are fitted the treadle-levers 4 5. Each lever consists, preferably, of a single bent arm provided at its outer end with an enlargement 6, which carries a pedal. The inner end of each treadle-lever is provided with an annulus or ring 8, and in the inner end of this annulus is formed a series of transverse recesses 9, one wall of each recess being inclined or tapered, as at 9^a. The ring or annulus of the treadle-lever is fitted loosely on the protruding end of the treadle-

shaft, and in each of the recesses of the annulus of each lever is placed a loose clutch-roller 10, which is pressed by a spring 10^a against the inclined wall 9^a of the recess and upon the periphery of the treadle-shaft in a manner to forcibly bind on the shaft when pressure is applied to the lever and thereby clutch the treadle-lever firmly to the shaft on the downstroke of said lever.

- 10 The treadle-levers are held on the protruding ends of the treadle-shaft by any suitable mechanical contrivances, and the clutch-rollers 10 in said levers are designed to make the levers fast with the treadle-shaft when pressure is applied to the levers in a downward direction; but after the levers have completed their downstrokes the clutch-rollers are free and the levers are permitted to return by the mechanism which will be presently described.
- 15 On one side of the bicycle and between the crank-hanger and one treadle-lever is fitted a sleeve 11, which is keyed to the shaft or rigidly fastened thereto in any suitable way. This sleeve furnishes a cylindrical surface 20 for the engagement of clutch-rollers in a sprocket-pinion 12. The hub of the sprocket-pinion 12 is fitted on the sleeve 11 to rotate or turn freely thereon when the sprocket-pinion moves in one direction; but said sprocket-
- 25 pinion is designed to be made fast with the sleeve by the employment of clutch-rollers 13 and springs 14. The hub of said sprocket-pinion is provided with a plurality of recesses 15, formed equidistant within the inner surface 30 of said hub, and each recess has an inclined wall or edge 15^a, against which the roller 13 within said recess is normally pressed by the action of the spring 14, thus causing the roller to wedge itself in place between 35 the periphery of the sleeve 11 and the inclined face 15^a of the sprocket-pinion hub.

The springs 14 are preferably of the form shown by the drawings—that is to say, each spring consists of a sheet or length of elastic 45 metal which is bent or doubled upon itself in a coiled form to provide a continuous spiral and adapted by its inherent elasticity to expand between a straight or radial wall of the recess and one of the loose clutch-rollers 13.

50 The sprocket-pinion has its teeth 12^a arranged centrally between its ends and radially with respect to the axis of the treadle-shaft, and the recesses 15 open through both ends of the hub of said sprocket-pinion. These recesses 55 are closed by the face-plates 16, which are applied to the ends of the sprocket-pinion hub and are secured in place by screws or other fastenings, said face-plates serving to prevent endwise displacement of the rollers and their 60 impelling-springs.

As is usual in safety-bicycles, the hub of the rear wheel is provided with a driven sprocket-pinion, (not shown,) and the sprocket-wheel 12^b on the treadle-shaft and said sprocket-pinion are operatively connected together by 65 a sprocket-chain 18.

20 designates the crank-shaft, which is ar-

ranged in a horizontal position in front of the treadle-shaft, and this crank-shaft is journaled in the bearing 1 on the inclined reach 70 of the bicycle-frame. The crank-shaft occupies a position parallel to the treadle-shaft in advance of the same and in a plane above the horizontal plane of said treadle-shaft.

In practice I may elevate the crank-shaft 75 about two inches above the treadle-shaft and about five inches in front of the same; but the distances between said shafts may be varied within the skill of the mechanic. The crank-shaft 20 and the treadle-shaft 3 are 80 connected together for rotation simultaneously by a sprocket-chain 21, which passes around the clutch sprocket-pinion 12 and a similar sprocket-pinion 22 on the shaft 20. The sprocket-pinion 22 is similar in construction to the sprocket-pinion 12 on the treadle-shaft, and these sprocket-pinions may be of corresponding size and provided with a like number of teeth to insure rotation of the crank-shaft 20 at the same speed with the 85 treadle-shaft 2. Such equal speed of the treadle-shaft and crank-shaft is not strictly necessary, however, because the treadle-shaft may be driven at a higher speed than the crank-shaft, if desired.

I provide the treadle-shaft with a pinion 12^c at the opposite end from the pinion 12, and the crank-shaft is provided with a similar pinion 22^a, which is connected with the pinion 12^c by a sprocket-chain 21^a. The crank-shaft 100 20 protrudes beyond its bearing 1 in the bicycle-frame, and to the ends of said shaft are attached the cranks 23. These cranks 23 are linked at 24 to the treadle-levers 4 5, each link being attached at one end by a pivotal 105 bolt 25 to its proper crank 23 and connected in a similar manner by a bolt 26 to its treadle-lever at a point intermediate of the length of the latter. The connection of the link to the treadle-lever may be adjusted by providing 110 two or more apertures in the treadle-lever, as at 26^a, through either of which apertures the pivotal bolt may be passed for the purpose of varying the leverage of the treadle-lever on the crank 23, carried by the shaft 20. 115

From the foregoing description it will be seen that my improved propelling mechanism for a bicycle embodies treadle-levers which are adapted to be clutched to the treadle-shaft on their downstrokes, that the crank-shaft is geared to the treadle-shaft to be rotated thereby, and that the crank-shaft is operatively connected with the treadle-levers. This connection of the crank-shaft with the treadle-levers provides a means for lifting the 120 treadle-levers after they have reached the limit of their downstrokes under the pressure applied thereto by the rider of the bicycle, and the described construction provides mechanical connections whereby the treadle-levers are positively raised by the action of the links and cranks connected to the crank-shaft, which is driven from the treadle-shaft, thus dispensing with the employment of a 125 130 135

spring-controlled ratchet-drum, which is generally used in propelling mechanism of the class to which my invention relates.

It will be seen that when one treadle-lever 5 is forced downward it operates to rotate the treadle-shaft, and the link and crank travel with said treadle-lever on its downstroke. When the treadle-lever reaches the full limit of its downward movement, the crank connected thereto passes the dead-center of the crank-shaft, and as the crank-shaft is impelled by connections with the treadle-shaft the crank on its upstroke serves, through the link 24, to raise the treadle-lever to its elevated position convenient for the application of power thereto by the bicycle-rider.

In my improved bicycle the propelling mechanism is so constructed and arranged that the rider can promptly start the bicycle 20 with a minimum loss of power, and the described mechanism enables the machine to be propelled without undue effort on the part of the rider when traveling upgrade.

The improved propelling mechanism may 25 also be employed to retard or arrest the travel of the vehicle. When it is desired to use the mechanism for this purpose, the operator applies pressure to the treadle-lever when the crank is on the upstroke, thus causing the 30 sprocket-pinion 22 or 22^a to pull on the sprocket-chain 21 or 21^a, the motion of which is communicated to the sprocket-pinion on the treadle-shaft through the sprocket-wheel 12^b and chain to the sprocket-pinion on the 35 rear hub.

I prefer to employ the construction of clutch mechanism shown by Figs. 6, 7, and 8 or by Figs. 9, 10, and 11. In this type of clutch mechanism I employ the sleeve 11 in connection with a divided clutch 27, reference being had more particularly to Figs. 6, 7, and 8. This clutch comprises a body which is divided or bisected longitudinally to form the two members 28 and 29. Each member 28 and 29 40 is provided with a central opening 30 and with a segmental solid wall 31. The members are adapted to be applied or fitted laterally together to have the solid walls 31 thereof fit within spaces provided in the members, and 45 the walls 31 of said members form ears 32, arranged to overlap each other and to be pivotally connected together by means of a pin 33, which passes through the members and the ears thereof. The member 28 is provided 50 with a slot 34, and the member 29 has a pintle 35, which passes through said slot in the member 28. The clutch member 28 is also provided with a pivotal stud 36, which constitutes the fulcrum for the treadle-lever, and 55 said treadle-lever is connected to the pintle 35 in a manner to have a limited turning movement on the fulcrum-stud 36 for the purpose of opening or closing the members or jaws 28 29 of the bisected clutch. The solid 60 walls 31 of the pivoted members or jaws 28 29 of the clutch are provided in their opposing faces or jaws with segmental recesses 37, each

recess having an inclined wall 37^a. These recesses are opposite to the sleeve 11, and in the recesses are fitted the spring-pressed 70 clutch-rollers 38 of the form substantially as described in connection with the clutch-pinion 12.

The member 28 of the clutch is provided with a guide rib or flange 39, which is adapted 75 to ride against the outer edge of the member 29. In this embodiment of the clutch the members or jaws are hinged together to move for a slight distance with relation to the sleeve 11, and the treadle-lever is connected with 80 the two members of the clutch so as to have its fulcrum on one clutch member and be loosely connected to the other clutch member in order that the lever on its upstroke may permit the clutch members to open slightly 85 and release the binding action between the rollers 38 and the sleeve 11. On the upstroke of the lever the clutch is free practically from engagement with the sleeve 11; but when pressure is applied to the treadle-lever in a 90 downward direction the lever turns on its fulcrum 36 and actuates the pintle 35 to close the members or jaws of the clutch and cause the clutch-rollers 38 to forcibly impinge against the sleeve 11, and thereby make the clutch, 95 the treadle-lever, and the sleeve fast with the shaft on which the clutch is mounted.

The clutch shown by Figs. 9, 10, and 11 is analogous in its operation to the clutch shown by Figs. 6, 7, and 8, and just described, 100 but the detailed construction of the clutch illustrated by Figs. 9, 10, and 11 is changed somewhat with a view to reducing the number of parts and simplifying the construction. This type of clutch embodies a cast-metal body 40, which consists of a face-plate 41, having a transverse circular opening 42 therein, a recessed plate 43 arranged parallel to the face-plate 41 and cut away at an intermediate point of its length to provide the recess 105 43^a, which is in line with the opening 42, and a transverse wall 44, which unites the plates 41 43 at one side of the body. This body is thus constructed to provide a longitudinal passage or chamber, which is open at one side and both ends of the body, and in this chamber is fitted a jaw 45. At one end of the body 40 the plates 41 43 have the ears or lugs 46, between which are fitted a corresponding lug 47 on the jaw 45, for the purpose of receiving a pivot 48, which attaches the jaw 45 to the body 40 in a manner to permit the jaw to have a limited movement or play within the body. The jaw 45 is of curved form, and its front end has a fork 49. 110 In the concaved side of this pivoted jaw is provided the recesses 50, to receive the spring-controlled rollers 51, which are adapted to bind upon the cylindrical surface of the sleeve 11, the latter passing through the opening and recess in the body 40. The treadle-lever is fitted in one open end of the body, 115 and said lever is fulcrumed, as at 52, to the body in a manner to have its rear extremity 120

fit in the fork 49 of the pivoted jaw 45. It will thus be seen that the lever is fulcrumed to one member of the clutch, (represented by the body 40,) while the end of the lever is connected to the other member of the clutch, (represented by the jaw 45.) The lever is thus adapted to have a limited movement or play on its fulcrum sufficient to permit the members or jaws of the clutch to open and close, whereby the movement of the lever in one direction operates to make the clutch fast with the sleeve 11, and its movement in the opposite direction is free or unrestrained by the clutch, because the jaws thereof are open sufficient for the clutch-rollers to ride upon the sleeve 11.

In lieu of the crank-and-link connection between the treadle-lever and the crank-shaft I may employ the slidable link connection illustrated by Figs. 14 and 15 of the drawings. This slidable link connection consists of a two-part extensible link 55, one member of which is adapted to be connected to the crank-shaft in a manner to ride therewith, while the other member is pivotally attached to the treadle-lever. The member 56 of the extensible link is preferably provided with a square socket to fit a corresponding end of the crank-shaft 20. Said member 56 is further provided with a longitudinal groove or channel 57. The other member 58 of the extensible link has a longitudinal socket 59, which receives the member 56 in a manner to permit the latter to have a sliding movement therein, and said member 58 carries a set-screw 63 or other equivalent stop, which is fitted loosely in the longitudinal groove or channel of the member 56 for the purpose of holding the two members in proper alignment to prevent the disconnection of the members when extended their full limit and to prevent the members from turning axially with respect to each other. The end of the channel or groove adjacent to the extremity of the link member 56 is closed by an abrupt wall or abutment 60, against which the end of the stop-screw may impinge, and the sliding movement of the two link members with respect to each other is cushioned under certain conditions by a coil-spring 61, which is contained in the socket of the member 58 in the path of the solid member 56.

I prefer to employ the crank-and-link connection heretofore described, and shown in Figs. 1 to 5, inclusive; but I may desire under some conditions of service to employ the extensible link shown by Figs. 14 and 15.

It is evident that changes in the form and proportion of parts and in the details of construction may be made without departing from the spirit or sacrificing the advantages of my invention, and I therefore reserve the right to make all such modifications and alterations as fall within the scope of my invention.

It will be understood that clutch-formed

sprocket-pinions 12 22 on the treadle and crank shafts may have equal numbers of teeth to cause the shaft 20 to rotate at the same speed as the treadle-shaft; but the numbers of teeth in the sprocket-pinion 12 may be diminished by one or more teeth with reference to the number of teeth in the other sprocket-pinion 22, thus allowing the shafts to be rotated at somewhat different speed and not require the operator to work the treadle-levers so fast.

Under some conditions of service of the propelling mechanism the clutch-formed sprocket-pinions on the shafts 3 20 are allowed to work loosely on said shafts; but when normal conditions prevail and the mechanism is operated to propel the bicycle the sprocket-pinions are clutched to the shafts in order to have the shaft 20 driven by the treadle-shaft for the purpose of giving the lift or upstroke to the treadle-levers.

It will be understood that either of the described forms of clutches may be employed in connection with the treadle-levers to make the same fast with the treadle-shaft on the downstrokes of the levers and to allow the clutches to remain idle on the upstrokes of said levers, the levers acting alternately in the driving of the shaft 3.

While the clutches are especially desirable and serviceable in the propelling mechanism, it is evident that such clutches or either of them may be used in other arts or relations where such a device is desirable.

Having thus described the invention, what I claim as new, and desire to secure by Letters Patent, is—

1. In a propelling and back-pedaling brake mechanism for bicycles, the combination with a treadle-shaft, and treadle-levers with means for clutching the same to said shaft, of a crank-shaft operatively connected with the treadle-levers, gearing between the crank-shaft and treadle-shaft, and clutch devices for making the gears fast with their respective shafts, substantially as described.

2. In a propelling and back-pedaling mechanism for bicycles, the combination with a treadle-shaft, and treadle-levers having clutch devices for making the same fast with the treadle-shaft, of a crank-shaft having link connections with said treadle-levers, sprocket-pinions fitted to the treadle and crank-shafts, and said pinions provided with clutch devices for making the same fast with their respective shafts, a sprocket-chain connecting said sprocket-pinions, and means for operatively connecting the treadle-shaft with a rear wheel, substantially as described.

3. In a propelling mechanism for bicycles, the combination with a treadle-shaft and treadle-levers, of a crank-shaft journaled in the bicycle-frame in advance of said treadle-shaft, sprocket-pinions provided with clutch devices and mounted on the treadle-shaft and the crank-shaft, a sprocket-chain connect-

ing said sprocket-pinions, and driving connections between the treadle-levers and the crank-shaft, substantially as described.

4. In a propelling mechanism for bicycles, 5 the combination with a shaft or sleeve, of a divided hinged clutch embracing said sleeve and having rollers which are confined within the clutch members and arranged to bind against the sleeve, and a treadle-lever operatively connected with the clutch members 10 to close the latter and make the rollers grip the sleeve, for the purpose described, substantially as set forth.

5. In a propelling mechanism for bicycles, 15 the combination with a shaft or sleeve, of a divided clutch which embraces said shaft or sleeve, and has its members hinged together to open or close a limited distance, clutch-rollers mounted loosely in one or both members 20 of said clutch and arranged to have contact with the shaft or sleeve, and a treadle-lever fulcrumed on one member of the clutch and connected with the other clutch member, substantially as and for the purposes de- 25 scribed.

6. A divided clutch consisting of overlapping members one of which carries a series of gripping-rollers, a hinge-pintle for uniting the members pivotally together, and a lever ful-

crumed in one clutch member and loosely connected with the clutch member which sustains the gripping-rollers, substantially as described. 30

7. A divided clutch having its members pivoted together and with one member formed at 35 its free end with a jaw, a lever fulcrumed in the other member and provided with a projection that fits in said jaw, and gripping-rollers carried by the jaw-formed clutch member, substantially as described. 40

8. The combination with a shaft or sleeve, 45 of a divided clutch having its members loosely fitted to, and hinged together at one side of, said shaft or sleeve and one of said members carrying a series of spring-pressed rollers arranged to bind on the shaft or sleeve, and a lever pivoted at a point intermediate of its length to one clutch member and loosely connected to the free end of the clutch member which sustains the gripping-rollers, substan- 50 tially as described.

In testimony that I claim the foregoing as my own I have hereto affixed my signature in the presence of two witnesses.

WILLIAM W. BROOKS.
